UNITED STATES PATENT OFFICE.

ALEXANDER KIRKALDY, OF NEW YORK, N. Y., ASSIGNOR OF ONE-FOURTH TO ROBERT S. FLETCHER, OF NEW YORK, N. Y.

ELECTROLYTIC PROTECTIVE MEANS FOR CONDENSERS.

Application filed November 3, 1927. Serial No. 230,767.

This invention relates to means of electrolytic protection for condensers and my improvements are directed to a system of bus bars connected in the form of a grid, said 5 bars being encased in insulation material and located in the respective headers of the condenser, and said bus bars being provided with a plurality of anodes that are removably attached thereto, to disperse the electrical current 10 conveyed to said anodes throughout the body of water that flows through said headers.

The grid composed of connected bus bars is connected to the condenser shell by supports that are suitably insulated therefrom and current is supplied to the bus bars by suitable electrodes.

In the drawings:

Figure 1 is a top view, partly in section, 20 of a condenser equipped with my improved system of connected bus bars and anodes detachably carried thereby.

Fig. 2 is a vertical section taken on the line 2—2 of Fig. 1 through the header that 25 is provided with the cooling water inlet and outlet means.

Fig. 3 is a vertical section taken on the line 3—3 of Fig. 1 through the header at the other end of the condenser and

Fig. 4 is an enlarged partial view of connected bus bars showing a detachable anode carried by one of said bars.

In said figures let 1 indicate the tubular shell of a condenser, 2, 3, respectively the end plates thereof, 4, 5 respectively the opposite plates carrying the series of water tubes 6, 7, and 8 the vertical partition separating the inflow and outflow compartments 9, 10 included in the header formed between plates 40 2 and 4, the compartment 9 having inlet 11 and the compartment 10 having outlet 12.

The condenser has the usual stay bolts 13, connecting header plates 2, 3, and is also provided with the usual steam inlet 14 and the outlet 15 for the product of condensation.

In the electrolytic system of protection against deterioration of the condenser I provide in the compartments 9, 10, and in the compartment 16 formed between plates 3, 5, 50 series of horizontal bars 17 and vertical bars

18 arranged in crossed relation, connected at their points of intersection, and lying in a vertical plane transversely of the condenser shell within said compartments respectively. The connected bars in each compartment thus 55 form groups or grids adapted to carry a plurality of anodes for the dispersion of electrical current throughout the bodies of water flowing through said compartments. Since the grids in all the compartments are similar 60 in character the description of one will apply to all.

It will be noted in Fig. 4 that the bars 17 and 18 are in close contact to thus have electrical conductive relation, said bars being connected as by bolts 19 (only one example of the connecting means being illustrated). Also it will be seen that anodes 20 are secured to the bars at a number of places thereon. In Fig. 4 a single example is given of the means 70 for attaching an anode to a bar, it being shown as removably secured thereto by means of a screw 21 that penetrates the bar and engages the anode, the anode lying in close electrical contact with the bar. The bars, excepting where they contact with each other and with the anodes are entirely wrapped or encased with insulation 22, so that said bars may not be themselves subject to the deteriorating effect which would ensue if they 80 were exposed, and so that the renewable anodes alone may be relied upon for the delivery of electrical current into the water compartment.

Suitable supports 23 of insulation material 85 are secured to the condenser shell 1 and partition 8, the bars 17, 18 being connected to these supports to hold the grid rigidly in its effective position.

As means for delivering electrical current 90 to the respective grids in their compartments I may employ an electrode 24 of suitable character, such for example as that shown and described in my application for patent filed concurrently herewith, such electrode being 95 insulated from the shell it penetrates, so that the flow of current must be from the anodes to the shell, thereby rendering the shell cathodic.

Variations within the spirit and scope of 100

my invention are equally comprehended by the foregoing disclosure.

I claim:

Electrolytic protection means for condensers comprising a system of connected metallic bars, insulating means for attaching said bars to a condenser, means for communi-

cating electrical current to said bars, anodes detachably carried by said bars, and insulating material that completely encases said bars and their connecting means while leaving said anodes exposed.

New York, November 2nd, 1927.

ALEXANDER KIRKALDY.
